W. J. Miller

United States Patent Office.

WILLIAM J. MILLER, OF WASHINGTON CITY, DISTRICT OF COLUMBIA.

Letters Patent No. 78,115, dated May 19, 1868.

IMPROVEMENT IN SASH AND SHUTTER-FASTENINGS.

The Schedule referred to in these Letters Patent and making part of the same.

TO ALL WHOM IT MAY CONCERN:

Be it known that I, WILLIAM J. MILLER, of the city and county of Washington, in the District of Columbia, have invented a new and improved Mode of Securing Window-Shutters and Sash; and I do hereby declare that the following is a full and exact description thereof, reference being had to the accompanying drawings, and to the letters of reference marked thereon, in which like parts are indicated by like letters in the several figures.

The nature of my invention consists in a certain device, to be hereafter described, whereby window-shutters may be fastened, as also the sash; said shutters and sash to be released from the inside of the window-sill, and the sash may remain locked whilst the shutters are open.

To enable others skilled in the art to make and use my invention, I will proceed to describe its construction and operation.

In the drawings—

Figure 1 represents a part plan of a window-sill, section of shutter, as also of the fastening, &c., &c.

Figure 2 is a partial section of lower part of sash, as also of the sill, on line *ky*, and the fastening of the sash; whilst

Figure 3 is an inside view of shutter-fastening.

In the drawings, *A* represents the window-sill, or a section of it. *BB*, partial sections of the shutters. *G*, a partial section of lower part of sash. *a* is a plate, attached to one of the shutters, having a projection, *b*, to pass through an opening in the front of lock, *C*, thus locking the shutter by means of projection *b* and pivoted bar *e*, upon the upper edge of which presses a spring, *f*. The part *d* of lock *C* is secured to the first riser of the sill, against which the shutters close, whilst the part *e* is at right angles or is horizontal. *g* is an angular projection, attached to and underneath part *e* of lock *C*, one face of same being parallel to face *d* of the said lock. This angular projection serves as a guide to lock-bar *e*, also as a bearing for the rod *h*, which also rests in the front face *d* of *C*. This rod *h* should be square where it passes through the cam or elevator *i* under the end of lock-bar *e*.

When the rod *h* is turned so as to throw the cam *i* upwards, it raises the pivoted lock-bar *e*, thus releasing the projection *b* of plate *a*, when the shutters can be opened. This position is shown in red lines in fig. 3. The projection *b* is so shaped that shutters can be closed and locked without it being necessary to turn the rod *h*, but they cannot be opened without turning said rod.

The bar or rod *h*, where it passes through the cam *i*, has been said should be square, or of such shape as to turn the cam *i* without the intervention of a wedge or set-screw.

j is a slotted plate, secured to the sill *A* directly under the sash. It has two downward projections, through which the rod *h* passes, and between which, on the said rod, is a hook, *k*. This hook can be slipped on the rod *h* to suit any width of sill.

l is another slotted plate, secured to bottom rail of sash *G*. It has a downward projection, which enters the slot in plate *j*, and over this downward projection the hook *k* catches, as seen in fig. 2, locking the sash.

The hook *k* is turned to the right or left at the same time that the cam *i* is turned up or down.

When the shutters are closed and locked the sash is also locked, but after the shutters are opened the sash can be locked again. Fig. 2 shows the sash locked.

Having thus described my invention, what I claim as new, and desire to secure by Letters Patent of the United States, is—

The combination of the shutter-catch *b*, lock *C*, rod *h*, hook *k*, and plates *l* and *j*, or the equivalents of said plates, constructed, arranged, and operated in the manner substantially as shown and described, and for the purpose of locking or unlocking shutters and sash from within the room.
